ATTORNEY.

UNITED STATES PATENT OFFICE

FREDERICK M. VENZIE, OF PHILADELPHIA, PENNSYLVANIA

FLOOR STRUCTURE

Application filed November 18, 1931. Serial No. 575,838.

This invention, generally stated, relates to a building construction and has more particular relation to flooring made up of pre-cast slabs which may be either of waterproofing material per se or provided with a coating or layer of waterproofing material.

One object of the present invention is to provide a simple, efficient, and comparatively inexpensive arrangement of parts for the rapid assembling by unskilled labor of flooring possessed of waterproofing characteristics.

A further object of the present invention is to provide an arrangement and construction of parts of the character stated in which adjacent pre-cast slabs are tied or coupled together by means of reinforcing rods or wires longitudinally considered.

A further object of the present invention is to provide a pre-cast slab of the character stated the under surface of which is provided with spaced, pendant, integral flanges which flanges have embedded therein longitudinally extended reinforcing rods the terminals of which rods extend beyond the slab ends for clinching with reinforcing rods of adjacent slabs.

A further object of the present invention is to provide a structure of the character stated in which there is provided intermediate adjacent slabs a vertically arranged apertured web for interlocking adjacent slab ends with respect to floor beams constituting part of the floor structure.

A still further object of the present invention resides in the providing of general details of structure and arrangement of parts as will hereinafter more fully appear.

The invention consists of the novel construction hereinafter more fully described and finally claimed.

The nature, characteristic features and scope of the invention will be more fully understood from the following description taken in connection with the accompanying drawing forming part hereof, and in which:

Fig. 1 is a view, principally in longitudinal section of flooring embodying the invention;

Fig. 2 is a fragmentary view in plan of the part shown in Fig. 1;

Fig. 3 is a fragmentary view of the under-side of the part shown in Fig. 2;

Fig. 4 is an end view, partly in section, of Fig. 2;

Fig. 5 is a view in side elevation of Fig. 3;

Fig. 6 is a fragmentary view illustrating the manner of tying together the reinforcing rods shown in Fig. 1;

Fig. 7 is a fragmentary view in elevation hereinafter referred to;

Fig. 8 is a view in section taken upon the line 8—8 of Fig. 7; and

Fig. 9 is a view in perspective of a tie piece hereinafter referred to.

For the purpose of illustrating my invention I have shown in the accompanying drawing one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

Referring to the drawing in detail, the reference numeral 10 designates spaced floor members as I-beams for supporting the novel pre-cast slabs 11 embodying the invention. These slabs 11 may be made of any suitable material, preferably possessing waterproofing characteristics. Each slab 11 is provided upon its under face and formed integral therewith with pendant, longitudinally extended ribs 12, as best seen in Figs. 3, 4, and 5. Embedded in each rib 12 is a longitudinally extended member 13, as a rod or wire. The ribs 12, as before stated, are arranged in spaced relation and the ends thereof are bevelled as at 14. Each reinforcing member 13 throughout the major portion of its extent parallels the bottom of a slab as clearly shown in Fig. 1. Each reinforcing member at its ends is deflected upwardly at an angle 15, see Fig. 1, and thereafter is extended outwardly as at 16 in a horizontal manner to parallel the major portion of the extent of said reinforcing member, and is thereafter extended upwardly in parallelism as at 17, as

best seen in Fig. 1. The object in having the ends of the reinforcing member extended as at 17 is that of providing means whereby a tie wire 18 may be adjusted with respect 5 to the up-turned ends of the reinforcing member to couple the precast slabs together, as best seen in Fig. 6.

The central rib of each slab has embedded therein a vertically extended plate 19 apertured as shown in Fig. 5 to lighten construction. This plate extends from the central rib upwardly and terminates short of the top of a slab as shown in Fig. 4. Both the upper and lower portions of said plate are 15 flanged as at 20.

Adjacent the abutting portions of the floor slabs there is provided a device as best seen in Fig. 9 which is made of wire and comprises a cross piece 21 and a pair of parallel 20 prongs 22. In practice these prongs 22 are introduced through one end of a floor slab, as best seen in Fig. 1, and the ends of the prongs 22 are turned over as at 23 beneath the flanges of a floor beam 10. In the connection it is to be noted that the cross bar 21 of this device, as best seen in Fig. 8, is embedded in the slab material. The above construction anchors the floor slab with respect to the floor beams 10. In practice a 30 cementitious flooring material 24 is applied over the flooring slabs 11.

In order to accommodate the cross bars 21 the slabs 11 are notched as at 25.

The slabs 11 in order to provide lateral 35 interconnection are notched as at 26 and provided with a rib 27 opposite to the notch 26 whereby the slabs may be interlocked one with respect to another.

What is claimed is:

40 1. In a building construction of the character stated, flanged floor beams, pre-cast slabs the ends of which are cut away to fit over the upper flanges of and be supported by said beams, said slabs having embedded 45 therein longitudinally extended reinforcing rods, the terminals of which rods extend first through the slab ends at an upwardly extending angle entirely free of the beam flange and thereafter are extended vertically beyond a slab end, means for tying together the vertically extended portions of said reinforcing rods of companion slabs, a cementitious fill covering said slabs including said coupled together ends of said reinforcing rods, each slab being provided laterally considered 50 with a notched portion, and a tie-piece accommodated in said notched portions the terminals of said tie-pieces being clamped beneath the undersides of the beam flanges.

60 2. In a building construction of the character stated, flanged floor beams, pre-cast slabs the ends of which are cut away to fit over the upper flanges of and be supported by said beams, said slabs being provided with 65 pendant spaced flanges each flange having

embedded therein longitudinally extended reinforcing rods, the terminals of which rods extend first through the slab ends at an upwardly extending angle entirely free of the beam flange and thereafter are extended vertically beyond a slab end, means for tying together the vertically extended portions of said reinforcing rods of companion slabs, a cementitious fill covering said slabs including said coupled together ends of said reinforcing rods, and an apertured and flanged reinforcing plate embedded in each of said slabs and extended into an intermediate of 70 said flanges. 75

3. In a building construction of the character stated, flanged floor beams, pre-cast slabs the ends of which are cut away to fit over the upper flanges of and be supported by said beams, said slabs being provided with pendant spaced flanges each flange having embedded therein longitudinally extended reinforcing rods, the terminals of which rods extend first through the slab ends at an upwardly extending angle entirely free of the beam flange and thereafter are extended vertically beyond a slab end, means for tying together the vertically extended portions of said reinforcing rods of companion slabs, a cementitious fill covering said slabs including said coupled together ends of said reinforcing rods, and an apertured and flanged reinforcing plate embedded in each of said slabs and extended into an intermediate of 80 said flanges, the said reinforcing rods following the general contour of said reinforcing 85 plate. 90

4. In a building construction of the character stated, metallic floor supports, pre-cast slabs the ends of which are cut away to fit over the upper flanges of and be supported by said beams, said slabs being provided with pendant spaced flanges each flange having embedded therein longitudinally extended reinforcing rods, the terminals of which rods extend first thru the slab ends at an upwardly extending angle entirely free of the beam flange and thereafter are extended vertically beyond a slab end, means for tying together the vertically extended portions of said reinforcing rods of companion slabs, a cementitious fill covering said slabs including 100 said coupled together ends of said reinforcing rods, and an apertured and flanged reinforcing plate embedded in each of said slabs and extended into an intermediate of 105 said flanges, the said reinforcing rods following the general contour of said reinforcing plate. 110

FREDERICK M. VENZIE.
